CLAIM

The design for a rechargeable remote control assembly with
charger, as shown and described.

DESCRIPTION

FIG. 1 is a top right perspective view of a remote control
assembly showing our new design with the charger removed
for the purpose of illustration.

FIG. 2 is a side elevation thereof;

FIG. 3 is a bottom plan thereof;

FIG. 4 is a top plan thereof;

FIG. 5 is a top front perspective view of the remote control
assembly with charger; and,

FIG. 6 is a top rear perspective view of the remote control
assembly with charger.
